OTTO S. SCHAIRER, OF PLUM TOWNSHIP, ALLEGHENY COUNTY, PENNSYLVANIA, AS
SIGNOR, BY MESNE ASSIGNMENTS, TO EXCEL PRODUCTS CORPORATION, A COR-
PORATION OF PENNSYLVANIA.

AUTOMOBILE SIGNAL DEVICE.

Application filed November 19, 1923. Serial No. 675,434.

My invention relates to signals of the kind that are used on automobiles and other vehicles to indicate that the vehicle is to slow down or stop, or is to turn either to the right or left.

The object of my invention is to provide a device of this character that shall be very simple, compact and economical in construction and neat and attractive in appearance, 10 by reason of the arrangement and small number of its parts, and that shall give unmistakable and distinctive indications of the intentions of the driver, preferably visible from both the rear and the front of the 15 vehicle.

In carrying out my invention I employ a signal casing having in either or both its front or rear faces three windows that are provided with distinctive cautionary, and directional indicators. The middle window is preferably red and is provided with the cautionary indicator in the form of the letter "S" or the word "Slow" or "Stop". The outer windows are preferably green and are 20 provided with arrows or V's respectively pointing to the right and to the left. Within the casing is a small lamp for illuminating the windows or indicators and shutters for selectively controlling the illumination 25 of the directional indicators, the shutters being actuated by electromagnets. By properly controlling the circuits the small lamp is used to illuminate the indicators to show whether the vehicle is to slow down, or to 30 turn to the right or to the left, and the signals are made more effective by their distinctive colors and their relative positions.

In the drawings,

Figure 1 is a view, partly in side elevation, 40 and partly in longitudinal vertical section, of a signal box embodying my invention,

Fig. 2 is a horizontal section therethrough taken on the line II—II of Fig. 1,

Fig. 3 is a view, in lateral section there- 45 through, taken on the line III—III of Fig. 1,

Fig. 4 is a view, in vertical longitudinal section, through a signal box embodying a modified form of my invention,

50 Fig. 5 is a view, in side elevation thereof, Fig. 6 is a view, in vertical lateral section

therethrough, taken on the line VI—VI of Fig. 4,

Fig. 7 is a fragmentary view, in plan, of an actuating device comprising a part of the 55 signal box embodying my invention, and,

Fig. 8 is a schematic diagram of connections of a control circuit employed with the device embodying my invention.

Referring to Fig. 1 of the drawings, a 60 casing 11 comprises a base portion 12 and an easily removable cover or top portion 13 that are respectively made of relatively thin sheet metal. A plurality of small machine screws 14 may be employed at the sides to 65 hold the two portions in proper operative positions relatively to each other. The base portion 12 has a pair of opposed upwardly and inwardly extending side flange portions 15 upon which is mounted a base 16 for receiving a small incandescent lamp 17 that constitutes the single light source provided in the signal box and that is located substantially centrally of the casing cover.

The cover portion 13 is provided also with 75 a plurality of upwardly and inwardly extending end flange members 18, the side portions of which are adapted to receive screws 14 to secure them to the ends of the casing 13. The portions 18 are spaced a suitable 80 distance apart and extend substantially one third of the length of the casing from each end thereof and are further adapted to support a portion of an operating mechanism to be hereinafter described in detail. 85

Each of the side walls of the casing 13 is provided with a plurality of substantially rectangular openings 19 therein, three in number. Each opening is covered by a transparent sheet 20 of celluloid or thin 90 glass. On the inner side of the sheet 20 on each of the outer openings 19 there is located a sheet of translucent green celluloid 21, having a design 22 thereon in the form of a horizontally outwardly extending arrow of a deep black color. On the inner side of the sheet 20 on the intermediate opening 19 there is located a translucent sheet 23 of red celluloid having a design 23a thereon in the form of the letter S of a deep black color. 95 When illuminated by the relatively high candle power source of light 17, the outer or

directional indicators will present a substantially black and horizontally-extending arrow against a green background, and the intermediate or cautionary indicator will present a substantially black S against a red background.

Frames 24, of relatively thin sheet metal and of substantially rectangular contour, are provided to hold the pairs of transparent and of colored celluloid sheets against the inner surface of the side walls of the casing, rivets 25 being employed to hold the frames 24 tightly against the celluloid sheets and against the casing.

Two vertically extending rods 26 are located within the casing 13 and are spaced substantially equi-distantly from each other and from the end walls of the casing. The upper end of each of the rods 26 is located in a suitable opening in the top portion of the casing 13 and the lower ends thereof are located in the end portions of the respective flanged parts 18. A pair of relatively light metal shutter members 27 are pivotally mounted on each of the rods 26 and are each of such height as to extend from the top surface of the flange portion 18 to the top part of the casing 13. The free vertical edge of each of the shutters 27 is provided with a small integral laterally-extending flange portion 28 that normally engages a vertically extending stop member 29, of Z-shape, suitably secured to the inner surface of the side portions of the casing 13 substantially as illustrated in Fig. 2 of the drawing. A small helical spring 31 is mounted on each of the rods 26 and is effective to yieldingly hold the two shutters in their normal aligned positions substantially as illustrated in Fig. 2.

A small electro-magnet 32 is supported by each of the end walls of the casing 13 midway of its height. The electro-magnet 32 may be of any suitable or desired construction, but is here shown as substantially ironclad and is held against the inner surface of the casing 13 by a small machine screw 33. Each electro-magnet 32 has a horizontally movable core member 34, the outer end of which is connected to the adjacent respective shutters 27 by pairs of links 35, the ends of which are respectively pivotally secured to a lug on one of the shutters 27 and to the end of the core 34. This construction provides in effect a toggle joint that is effective, upon energization of the electro-magnet 32, to move the cooperating pair of shutters 27 from their aligned positions as illustrated by the full lines in Fig. 2 to the position illustrated by the broken lines in the right hand side of the same figure.

If desired, the movement of the core member may be arrested by an integral portion 65 of the electro-magnet structure or the outer

ends of the shutters 27 may strike angularly disposed and vertically-extending reflector members 36 that have one edge secured to the end portions of the casing. The angular position of the members 36 is such that they 70 are in substantial alignment with the shutters 27 when the two members are in operative engagement in substantially the positions illustrated in Fig. 2. The inner surfaces of the shutters 27 may be polished and 75 will provide reflecting surfaces for light produced by the light source 17 whereby the signal indications of V-shape adjacent the ends of the casing will be illuminated when the light source 17 is energized and the shutters 27 are in their normal operative positions indicated by the broken lines in Fig. 2.

Each of the electro-magnets 32 is provided with a lead wire 37, the outer end of 85 which is secured to a terminal member 38 comprising a machine screw insulatedly mounted in the flange portion 18 and a plurality of nuts mounted thereon. The other end of the winding of the electro-magnet is 90 connected to the casing, providing a ground return.

Any suitable or desired terminal construction may be employed but I have illustrated a specific embodiment thereof comprising a 95 longitudinally-extending grooved bar 39, of electric-insulating material, located intermediate the side portions of the base 12 and secured against the bottom thereof by screws 41. The grooved bar 39 is provided 100 with a plurality of terminal members, each comprising a short machine screw 42 and a plurality of nuts 43 mounted thereon, together with a spring contact member 44, one end of which is securely held by the 105 nuts 43 against the upper surface of the bar 39. The free ends of each of the spring contacts 44 are respectively adapted 110 to engage one of the terminal structures 38 or the central terminal of the lamp socket 115 17.

A plurality of lead wires 45 are connected to the respective terminals 42 and may be combined into a unitary multiple-conductor 115 46 outside of the casing 13, from which the conductor 46 may extend to a suitable source of supply of electric energy 47 and suitable control devices 48, shown schematically only in Fig. 8 of the drawings.

Referring more particularly to the modified form of device as illustrated in Figs. 4 to 7 inclusive, substantially the same form of base portion 12, of casing 13, and of terminal structures supported thereby is employed as was described for the device 12 illustrated in Figs. 1 to 3 inclusive. A single light source 17 is provided, mounted in a base 16 substantially centrally of the casing 11 as was hereinbefore described.

Each of the side walls of the casing has 13

a plurality of substantially rectangular openings 19 therein. There are preferably three openings 19, the two outer ones being provided with directional indicators and the 5 intermediate opening being provided with cautionary indicators to be hereinafter described. Relatively thin translucent sheets 21 of the translucent green celluloid are so located as to cover each of the outer openings 19 and a similar sheet 23 of translucent red celluloid is so located as to cover the intermediate opening. 10

Plates 49, of relatively thin sheet metal, are located immediately adjacent to and inside 15 of the celluloid sheets 21 and 23, and are severally provided with a plurality of spaced perforations therethrough. The two outer perforations 22, adapted to act as directional indicators, are in the form of a horizontally and outwardly extending V and the 20 intermediate perforation 23^a, adapted to act as a cautionary indicator, the form of the letter S. The upper and the lower edges of each of the plates 49 are bent to channel 25 form with overhanging edges to constitute a supporting means and track for a movable shutter 51 located within the inturned edges of the member 49. The member 51 has the intermediate portion thereof cut out in substantially lozenge form, as illustrated more 30 particularly in Fig. 4 of the drawings, the horizontal dimension of the portion cut out being slightly less than the distance between the perforations of V shape in the member 35 49 whereby they are normally covered. The edges of the members 49 adjacent to the ends of the casing 13 are held tightly against the side portions of the casing by rivets 52.

Electro-magnets 32 are secured against 40 the inner surface of each of the end portions of the cover member 13 by small machine screws 33, the electromagnets being mounted, (substantially midway) of the height of the casing. A movable core member 34 for each 45 electro-magnet 32 has its outer end secured against a laterally-extending bent metal bar 53, the outer ends of which are secured in any suitable manner to the respective movable shutters 51. A helical spring 54 is 50 provided between each bar 53 and the outer end of the electro-magnet 32 to return the core members 34 and the shutters 51 to their normal inoperative positions. This position of each of the shutters is illustrated in Fig. 55 4 of the drawing, in which position the two signal indications 22 are both covered and are therefore not visible.

Referring more particularly to the device illustrated in Figs. 1 to 3 inclusive, the 60 operation thereof is substantially as follows; the respective parts of the device being illustrated in their normal inoperative positions by the full lines in Fig. 2 of the drawing. If the operator of a motor vehicle with 65 which my signal device is associated desires

to signal to the operator of a following vehicle that he intends to stop, he suitably actuates a switch that may be located closely adjacent to one of the foot pedals of the motor vehicle whereby a circuit is closed 70 through the light source 17. This switch is preferably of the type disclosed and claimed in a co-pending application, Serial No. 653,500, filed July 24, 1923, by Harry R. Van Deventer and Robert M. Warren. I 75 have illustrated a plurality of switches 48 in Fig. 8 of the drawings that may be operated as desired by an operator.

When the intermediate switch 48 is closed 80 a circuit is established through the lamp 17 only, and an observer will see a black S against a red background, thus providing a visual cautionary indicator. A resistor 55 may be connected in this circuit and have substantially the same resistivity as one of the electro-magnets 32, thereby ensuring substantially the same brilliancy of the lamp 85 when it is energized in conjunction with one of the electro-magnets 32 or when it is energized alone. 90

In case the operator wishes to signal to the operator of a following vehicle that he intends to make a right hand turn, he actuates the right hand switch 48 or a suitable switch box to energize not only the light 95 source 17 but also the right hand electro-magnet 32. Upon energization of this electro-magnet it attracts its armature core, causing it to move inwardly and to move the shutters from their normal alined positions to the positions illustrated by the broken lines in Fig. 2. In this position the inner surfaces of the shutters 27 and of the members 36 act as reflecting surfaces for the rays of light from the light source 17 and the two outer openings in the front and the rear walls of the casing adjacent to the right hand end of the casing are thereby illuminated; and observers at the front and at the back of the vehicle will 100 see a black S against a red background and a black arrow against a green background, the latter pointing in the direction of the intended turn of the vehicle. 105

In case the operator desires to signal that he intends to make a left-hand turn, the left hand switch is actuated to energize the light source 17 and the left hand electro-magnet, thereby causing not only the central compartment, but also the left hand compartment to be illuminated. An observer will see a black S against a red background and a black arrow pointing to the left against a green background, thereby giving a composite visual indication comprising a cautionary and a signal or directional indicator. 115 120

Hence when the operator of a vehicle carrying a signal device embodying my invention signals his intention to make a right 130

hand or a left hand turn he does so by a visual two part signal comprising two distinct elements: first, by two signal indicators differing in color, second, by a directional indicator whose position relatively to a cautionary indicator indicates the direction of an intended turn of the vehicle.

Referring more particularly to the modification illustrated in Figs. 4 to 6 inclusive, 10 the same type of switch is employed to control the energization of the respective signal indications as has hereinbefore been described. If the operator energizes the single light source only, a single cautionary signal 15 indication, comprising a red **S**, is given to an observer standing either in front of or behind the motor vehicle with which the signal device is operatively associated.

In case the operator desires to signal his 20 intention of making a right hand turn he actuates one of the switches 48, or a switch box, to energize not only the single light source but also the right hand electro-magnet 32. The movable core of the electro- 25 magnet is attracted and moves the two shutters 51 toward the right by means of the bar 53. The right hand signal indication 22, of **V**-shape, is thereby uncovered and the light from the single light source shines 30 through the directional indicator of **V**-shape and through the celluloid of green color at the end of the casing as well as through the indicator of **S**-shape and the red celluloid. In this case we obtain the illumination of 35 two signal indications, a cautionary one comprising a red **S** and a directional one comprising a green **V**. In case of a left hand turn, the single light source and the left hand electro-magnet 32 are simultane- 40 ously energized whereby the shutters 51 are

moved to the left uncovering the left hand **V** and again producing two distinctive indicators of different colors.

My invention thus provides a relatively simple device, of compact structure, comprising a single light source only that is effective to illuminate either one or a plurality of distinctive signal indications to indicate intended movements of the vehicle. 45 My device comprises also a plurality of electro-magnets selectively energized to render visible signal indications illuminated by a single light source centrally located relatively to the signal indications that are of different colors and that are specifically 50 positioned relatively to intended turns of the vehicle.

Various modifications may be made herein without departing from the spirit and scope 55 of my invention, and I desire that only such limitations shall be placed thereon as are imposed by the prior art.

I claim as my invention:

A signal box comprising a casing having 60 front and rear walls, a plurality of symmetrically spaced visual indicators in each of said walls, a single light source located substantially centrally in said casing, a plurality of movable shutters in said casing, 65 having reflecting surfaces, a combined shutter-step and reflector member for each of said shutters, and means for moving said shutters against said stops to permit said light source to render visible a plurality of indicators, said shutters serving also as reflectors when so moved.

In testimony whereof, I have hereunto 70 subscribed my name this 13th day of November, 1923.

OTTO S. SCHAIRER.
